AUTOMATIC MOP WRINGER

Albert Palmer, Alburg, Vt.

Application August 26, 1937, Serial No. 161,151

5 Claims. (Cl. 15—261)

The invention aims to provide a new and improved device for application to a bucket or the like, for the purpose of wringing a floor mop.

In carrying out the above and, a further object is to provide a novel construction which will automatically exert squeezing pressure upon the mop, simply by inserting said mop and pushing downwardly upon its handle.

A still further object is to provide a construction which is rather simple and inexpensive, yet easily operated, efficient and durable.

With the foregoing in view, the invention resides in the novel subject matter hereinafter described and claimed, description being accomplished by reference to the accompanying drawings.

Fig. 1 is a perspective view of the wringing device, showing the bucket with which it is to be used, in dotted lines, said wringing device being shown in position to receive a mop.

Fig. 2 is a vertical sectional view through the wringing device and the bucket showing the mop inserted in dotted lines and illustrating the mop squeezing parts in operative position.

The construction selected for illustration will be rather specifically described, with the understanding however, that within the scope of the invention as claimed, numerous variations may be made.

A horizontally elongated frame 5 is provided to rest upon a bucket or the like 6, and if desired appropriate means (not shown) may be provided for connecting said frame and bucket. If the usual bucket handle be sufficiently long to swing upwardly over the frame 5 and parts carried thereby, said handle may be used for carrying both the bucket and the entire wringing device. Otherwise said wringing device may be provided with a suitable handle (not shown) which will serve as carrying means for both the wringing device and the bucket if the latter be connected with the frame 5.

The side bars of the frame 5 are denoted at 7 and the end bars at 8, and over one of these end bars, a suitable guide 9 is preferably provided to guide the mop into the bucket for "slushing". The side bars 7 are provided near one end of the frame with upstanding posts 10 and are provided near the opposite end of said frame with similar posts 10, for a purpose to appear.

A U-shaped frame 11 is provided to extend into the bucket 6 and to project somewhat above said bucket, the side arms 12 of said frame 11 being offset outwardly at their upper portions 55 and having said upper portions suitably secured

at 13 to the intermediate portions of the side bars 7 of the frame 5.

A horizontally elongated carriage bar 14 extends between the lower portions of the arms 12 and is slidably connected with said arms, 5 preferably by providing it with slots 15 through which these arms pass. The ends of the bar 14 are connected by coiled springs 16 with suitable parts of the frame structure, said springs acting to yieldably hold said bar 14 in a raised position 10 (Fig. 1). In the present disclosure, the upper ends of the springs 16 are engaged with eyes 17 at the juncture of the arms 12 with the side bars 7, and said eyes may well constitute portions of eye bolts or the like for securing said arms and 15 side bars together.

Two swingable arms 18 are disposed at one side of the carriage bar 14 and incline steeply therefrom through one end of the frame 5, and two additional swingable arms 18^a are disposed 20 at the opposite side of said bar 14 and incline steeply therefrom through the other end or through the intermediate portion of said frame 5. Bolts 19 pass loosely through openings in the lower ends of the arms 18 and 18^a and pass 25 through other openings in the bar 14, and coiled over-load springs 20 are mounted on said bolts. This construction permits the upper ends of the arms 18 to swing toward the upper ends of the arms 18^a and vice versa, and also permits the 30 lower ends of said arms 18 to yield away from the lower ends of the arms 18^a and vice versa, to relieve strain on the parts when wringing a mop, as will be hereinafter more apparent.

Suitably secured to the upper portions of the 35 arms 18, is a wall 21, and a similar wall 21^a is secured to the upper portion of the arms 18^a, the wall 21 being preferably of greater height than the wall 21^a and being curved to constitute a "back stop" 22 which is instrumental in guiding 40 the mop into the space between the two walls 21 and 21^a. A bottom 23 extends between the lower portions of the walls 21 and 21^a and cooperates therewith in forming a receptacle to receive the mop. While this bottom may be mounted in any 45 suitable way, I have shown it secured to the lower edge of the wall 21 and passing under the wall 21^a, said bottom being provided with slots 24 through which the arms 18^a pass. Preferably a substantially U-shaped reinforcing frame 25 supports the bottom 23 and is secured at its ends to the arms 18. 50

Two horizontally elongated carriages 26 are slidably connected at their central portions with the upper end portions of the side arms 12 of 55

frame 11. Levers 27 are fulcrumed between their ends at 28 to the carriages 26, at one end of the latter, said levers declining steeply toward the end of the frame 5 which is provided with the 5 posts 10, the lower ends of said levers being connected with the upper ends of said posts by pivoted links 29. The upper ends of the levers 27 are connected suitably with the upper portions of the arms 18, a rock shaft 30 integral with said levers being engaged with suitable arm-carried brackets 31 for this purpose, in the present showing.

Additional levers 27^a decline steeply toward the end of the frame 5 which is provided with the 15 posts 10^a, the intermediate portions of these levers being fulcrumed at 28^a to the ends of the carriages 26 remote from the levers 27. The lower ends of these levers 27^a are connected with the upper ends of the posts 10^a by suitable hanger-links 29^a. The upper ends of the levers 27^a are 20 pivotally connected with the upper ends of the arms 18^a in any suitable manner. In the present showing, it may be considered that the rod 30^a is secured to the arms 18^a and to the wall 21^a and 25 that the upper ends of the levers 27^a are pivotally connected with the ends of said rod 30^a.

By normally holding the carriage bar 14 in a raised position, the springs 16 similarly hold the arms 18 and 18^a, the walls 21 and 21^a, and the 30 bottom 23 in a raised mop-receiving position. When the mop is placed between these walls 21 and 21^a and pushed downwardly, said walls 21 and 21^a, the bottom 23, the arms 18 and 18^a, and the carriage bar 14 all move downwardly together, during which movement, the levers 27 and 27^a are caused to swing from the 35 position of Fig. 1 to that of Fig. 2, with the result that said levers inwardly swing the arms 18 and 18^a and the walls 21 and 21^a to effectively squeeze 40 surplus water from the mop. As soon as the downward pressure upon the mop handle is relieved, the springs 16 return the carriage 14 and parts connected therewith to raised position, and at the same time, the levers 27 and 27^a and associated parts return to their normal positions, 45 again separating the walls 21 and 21^a and again placing them in readiness to next receive the mop.

It will be seen from the foregoing that novel and advantageous construction has been disclosed 50 for providing an expandible and contractible mop-squeezing receptacle which is movable by a downward push on the mop handle, from a normally raised mop-receiving position to a lowered mop-squeezing position. Obviously this same general 55 result could be obtained with variations over the present disclosure and it is therefore to be understood that this disclosure is illustrative rather than limiting.

When the specific construction herein shown or 60 a similar construction is employed, the levers 27 and 27^a may have a tendency to continue inwardly pushing the upper ends of the walls 21 and 21^a after the lower ends of said walls have moved inwardly as far as the compressed mop will 65 permit. When this occurs, the over-load springs 19 permit the lower ends of the arms 18 and 18^a to move away from each other, relieving strain upon them and associated parts.

It is preferable to suitably connect the side 70 arms 12 of the frame 11 with the side bars 7 of the frame 5, by suitable braces 32 but if 12 and 7 should be welded together or secured in some other way which would not require bracing, said braces could of course be dispensed with.

75 Excellent results may be obtained from the

general construction shown and described, but attention is again invited to the possibility of making variations within the scope of the invention as claimed.

I claim:

1. A mop wringer comprising a supporting frame having a vertical track, a carriage slideable along said track, arms connected with and extending upwardly from said carriage for movement toward and from each other, the upper 10 ends of said arms being provided with spaced mop-squeezing members, an additional vertical track carried by said frame, an additional carriage slideable vertically on said additional track and elongated in the direction in which said 15 arms are swingable, upwardly converging inclined levers fulcrumed between their ends to the ends of said additional carriage, hanger links hung from portions of said frame and pivoted to the lower ends of said levers, and means pivotally connecting the upper ends of said levers with said arms, whereby downward pushing of said arms will cause said levers to swing said arms inwardly to squeeze the mop, and restoration of said arms to raised position will cause 20 said levers to swing said arms outwardly to release the mop.

2. A mop wringer comprising supporting means having a vertical track, a carriage slideable along said track, arms extending upwardly 30 from said carriage for movement toward and from each other, means operatively connecting said arms and carriage and including portions yieldable under over-load, the upper ends of said arms being provided with spaced mop-squeezing members, and means operatively connected with said arms and said supporting means for swinging said arms inwardly toward each other when they are pushed downwardly to cause said mop-squeezing members to squeeze 40 the mop and for swinging said arms outwardly away from each other when they are restored to raised position.

3. A mop wringer comprising a supporting frame having a vertical track, a carriage slideable along said track, arms connected with and extending upwardly from said carriage for movement toward and from each other, the upper ends of said arms being provided with spaced mop-squeezing members, an additional 50 vertical track carried by said frame, an additional carriage slideable vertically on said additional track and elongated in the direction in which said arms are swingable, upwardly converging inclined levers fulcrumed between their 55 ends to the ends of said additional carriage, means operatively connecting the lower ends of said levers with said frame, and means pivotally connecting the upper ends of said levers with said arms, whereby downward pushing of said arms will cause said levers to swing said arms inwardly to squeeze the mop, and restoration of said arms to raised position will cause said levers to swing said arms outwardly to release the mop.

4. A mop wringer comprising a supporting 65 frame having a vertical track, a carriage slideable along said track, arms connected with and extending upwardly from said carriage for movement toward and from each other, the upper ends of said arms being provided with spaced mop-squeezing members, an additional 70 vertical track carried by said frame, an additional carriage slideable vertically on said additional track and elongated in the direction in which said arms are swingable, and means opera- 75

tively connecting the ends of said additional carriage with said arms and said frame for swinging said arms inwardly to squeeze the mop when said arms are pushed downwardly, and for again 5 swinging said arms outwardly to normal position when said arms are restored to raised position.

5. A mop wringer comprising a horizontal frame to rest on a bucket rim, two spaced vertical tracks secured to and projecting downwardly 10 from said frame for reception within the bucket, a depressible carriage bar extending horizontally

between and slidably connected with said tracks, upwardly diverging arms pivoted to said carriage bar, a mop receptacle having spaced side walls secured to said arms, and means operatively connecting said arms with said horizontal frame for inwardly swinging said arms and side walls when the receptacle and arms are depressed, and for again outwardly swinging said arms and side walls when said receptacle and arms are restored to raised position.

ALBERT PALMER.
